UNITED STATES PATENT OFFICE.

JOHN D. WARREN, OF CHICAGO, ILLINOIS.

DESIGN FOR A CABINET.

SPECIFICATION forming part of Design No. 35,701, dated February 4, 1902.

Application filed December 23, 1901. Serial No. 87,046. Term of patent 7 years.

To all whom it may concern:

Be it known that I, JOHN D. WARREN, a citizen of the United States, residing in Chicago, in the State of Illinois, have invented and produced a new and original Design for a Cabinet, of which the following is a full, clear, and exact description, reference being had to the accompanying drawing, forming part of this specification.

10 The drawing is a perspective view illustrating my design.

The leading or material feature of my design is a cabinet containing two series of wide drawers of varying depths located in the lowermost portion thereof and extending the full width of the space between its sides and two series of narrow drawers located in the upper portion of the cabinet on opposite sides of a parting-line and a shelf located between the lower wide drawers and the upper narrow drawers.

1 designates the side walls of the frame, that inclose a base 2 and are surmounted by a top 3.

4 designates lower shallow drawers extending the full width of the space between the 25 side walls 1, and 5 designates drawers surmounting the drawers 4 and of the same width, but of greater depth.

6 designates the narrow drawers of the upper series, located in two tiers at opposite sides 30 of a partition 7.

8 is a shelf located between the lower wide drawers 5 and the two upper series of narrow drawers 6.

I claim as my invention—

35 The design for a cabinet substantially as herein shown and described.

JOHN D. WARREN.

In presence of—

A. C. HUTCHISON,
W. C. DUDLEY.
